JOHN J. FLANIGAN, OF CHICAGO, ILLINOIS, ASSIGNOR TO DUPLICATOR MANUFACTURING COMPANY, OF CHICAGO, ILLINOIS, A CORPORATION OF WEST VIRGINIA.

MULTIPLE COPYING-MACHINE.

1,226,649.

Specification of Letters Patent. Patented May 22, 1917.

Application filed May 27, 1916. Serial No. 100,836.

To all whom it may concern:

Be it known that I, JOHN J. FLANIGAN, a citizen of the United States, residing at Chicago, in the county of Cook and State of Illinois, have invented certain new and useful Improvements in Multiple Copying-Machines, of which the following is a specification.

This invention relates to the art of multiple copying machines of the hectograph type, and has reference more particularly to that class of such machines employing a flat printing bed supported on a suitable frame, a duplicating band or apron stretched thereover, and a removable impression device including a platen roll that is normally rolled over the bed in order to impress both the master sheet and the copy sheets on the gelatin apron that is supported by the bed.

My present improvements relate more particularly to an impression device of that type which employs a pair of paper gripping rolls that are separated to permit the introduction of one end of a paper sheet between them, and one of which rolls is then lowered, carrying the end of the paper sheet with it, into rolling contact with the duplicating band or surface to roll over and impress the paper sheet on the latter, thus constituting a platen roll. Heretofore, so far as I am aware, in platen carriages of this type, it has been customary to mount the spring-pressed gripping roll of this pair in a carriage frame that is slidable over the bed of the machine, and to mount the platen roll in and between the arms of a bail-shaped yoke that itself is pivoted in and swings relatively to the carriage frame. A leading object of my present invention is to simplify and cheapen this construction by doing away with the pivoted yoke that carries the platen roll, mounting the latter directly in the frame of the carriage, mounting the spring-pressed gripping roll with capacity for bodily lateral movement in the carriage frame, and providing fulcrum points and cam devices on the bed frame of the machine for co-operation with the platen carriage and the spindles of the two rolls so that, on tilting or swinging the platen carriage in one direction the two rolls may be bodily separated to allow the introduction of the paper sheet, and on tilting or swinging the platen carriage in the opposite direction the two

rolls may grip the paper sheet and carry the latter, in properly squared or aligned position, down onto the printing bed. Other minor objects and advantages of the invention will be apparent to those skilled in the art from the following description taken in connection with the accompanying drawings, forming a part of this specification, in which—

Figure 1 is a top plan view showing the platen carriage in starting position at the head end of the machine, and a sheet of paper introduced therein;

Fig. 2 is a longitudinal section taken on the line 2—2 of Fig. 1;

Fig. 3 is a fragmentary side elevation showing the platen carriage and the coöperating stationary devices at the head end of the machine for effecting the positioning of the platen carriage and the opening of the rolls for the introduction of the paper sheet;

Fig. 4 is a detail vertical longitudinal section through the head end of the bed and the platen carriage, showing the latter part-way advanced over the bed in the operation of rolling out a paper sheet thereon;

Fig. 5 is a side elevation of the parts appearing in Fig. 4, also showing the platen carriage in dotted lines in its initial or starting position;

Fig. 6 is a sectional detail on the line 6—6 of Fig. 5, showing a brake applied to the platen roll to prevent it from turning on its own axis until the paper sheet has been brought by it into contact with the printing bed;

Fig. 7 is a detail sectional view on the line 7—7 of Fig. 5, more particularly illustrating the manner and means of mounting the spring-pressed gripping roll.

Referring to the drawings and first briefly describing the stationary frame structure, 10 designates each of a pair of parallel vertical side plates that are rigidly connected and spaced at their lower portions by cross bars 11 (Fig. 2), the ends of which are turned down to form legs 12 and are secured to the plates by bolts or rivets 13. 14 designates each of a pair of distance rods that rigidly connect and space the upper portions of the side plates 10 above the cross bars 11, 105 and form supports for a removable bed plate 15. This latter, as is best shown in Figs. 3 and 4, has attached to its opposite sides near

its front end a pair of upstanding plates 16, each formed with an inwardly extending horizontal attachment member 17 by which it is secured to the bed plate 15 through 5 screws or rivets 18, and a depending bracket 19 having a vertical slot 20 by which the bracket straddles and rests upon the forward distance rod 14. To the opposite sides of the bed plate 15 near its rear end are similarly attached depending brackets 21 that are horizontally forked or slotted, as shown at 22, to engage and rest upon the rear distance rod 14 under a horizontal sliding movement. The bed plate 15 carrying the 10 guide plates 16 and integral supporting brackets 19 may be removed from the machine frame by raising its forward end until the brackets 19 clear the forward distance rod 14, and then, by a slight forward movement, the rear brackets 21 are drawn clear 15 of the rear distance rod 14. The bed plate is put in place by the converse of these operations performed in the inverse order in a manner readily understood. The bed 20 plate is preferably furnished with a cloth covering 23 stretched thereover and suitably secured thereto; and the bed plate and its attached parts may readily be tilted up on its rear brackets 21 and the rear distance rod 25 14, operating as a hinge, to permit access to an underlying storage receptacle 24 supported in straps or hangers 25 between the side plates 10 of the machine frame.

Over the bed plate is stretched the usual 30 gelatin duplicating apron or band 26, the end portions of which are wound on a pair of duplicate spools 27, one of which is located at the head end of the machine and constitutes the receiving spool while the other 35 is located at the tail end of the machine and constitutes the delivery spool. When the band has been exhausted from the delivery spool and wound up on the receiving spool, the two spools may be removed and 40 interchanged and the band is then rewound in the same direction, or the spools may be left in place and the band rewound in the reverse direction.

The parts thus far described, with the exception 45 of the vertical plates 16 hereinafter more particularly described, are substantially identical with parts shown, described and claimed in my former Patent No. 1,197,617, dated Sept. 12, 1916; and as the specific structural details of these parts are not concerned with my present invention, they need not be more fully described herein. As stated in the preamble of this specification, my present improvements have to do 50 more particularly with a novel construction of impression device and co-operating stationary devices represented by the plates 16 for positioning the platen carriage and effecting and controlling the opening and 55 closing movements of the rolls, whereby I

am enabled to dispense with the employment of a pivoted handle-operated yoke in the carriage frame for raising and lowering the platen roll.

Referring now more particularly to the novel features wherein my present invention resides, 28 and 29 designate the side members and 30 each of the end members of a rectangular carriage frame, the side member 28 being provided with a centrally disposed handle 31 and the opposite side member 29 having secured thereto a pan 32 serving as a guide for the introduction of the paper sheet represented by 33. In and between the side bars 30 of the carriage frame is journaled the platen roll 34, on the ends of which are projecting spindles 35 that coöperate with substantially vertical slots 36 formed in the lower sides of the stationary plates 16 in a manner hereinafter more fully described. On the inner sides of the side bars 30 of the carriage frame are pivoted at 37 a pair of sector-shaped arms 38, in slot bearings 39 of which is mounted the gripping roll 40 that lies in parallelism with the platen roll 34; said gripping roll also being provided at its ends with spindles 41 which coöperate with cam surfaces 42 and notches 43 formed in the plates 16 in the manner hereinafter described. The gripping roll 40 is normally pressed toward the lower ends of its bearing slots 39 by springs 44 in order to insure a proper gripping action on the paper when the gripping roll is permitted to move toward the platen roll in the operation of carrying the head end of the sheet down onto the printing bed. The arms 38 are normally urged in a direction to carry the gripping roll toward the platen roll by means of tensile springs 45 connected at one end to the upper corners of the arms 38 and at the other end to lugs on the side bar 29 of the carriage frame. The extent of swinging movement of the arms 38 is limited in one direction by the engagement of a shoulder 46 on the lower edge of the arm 38 with a stop pin 47 carried by the end bar 30 of the carriage frame and in the other direction by the engagement of a similar shoulder 48 with the same stop pin. On the inner sides of the plates 16 are fulcrum pins 49 that engage notches 50 in the lower edges of the end bars 30 of the carriage frame to facilitate tilting or rocking of the latter. Pivoted on the fulcrum pins 49 are a pair of arms 51 which support at and between their free ends an angle-shaped gage-bar 52 that normally lies directly across the head end of the printing bed and serves to square the end edge of the paper sheet 33 when it is introduced into the impression device in the manner clearly shown in Fig. 2. The pivoted supporting arms 51 of the gage-bar are supported in normal or working position

by pins 53 in the inner sides of the plates 16, as clearly shown in Fig. 2.

It will be observed that the entire impression device may be bodily applied to and removed from the bed and frame of the machine, as in the former application hereinabove referred to. In the operation of the machine, the platen carriage is placed on the bed and drawn backwardly until it lies between the plates 16 with the notches 50 engaging the fulcrum pins 49, at which time the parts are in the relative positions indicated by dotted lines in Fig. 5. The handle 31 is then depressed, tilting the carriage frame on the fulcrum pins 49 until the parts assume the relative positions shown in Figs. 2 and 3. During this movement the projecting spindles 35 of the platen roll move up into engagement with the closed ends of the slots 36, thereby limiting the extent of tilting movement of the frame and preventing forward or backward movement of the latter while in this position. At the same time the projecting spindles 41 of the gripping roll ride over the inclined or cam surfaces 42 against the pull of the springs 45 until said spindles pass the rounded ends of the cams 42 and fall into the notches 43 under the tension of the springs 43. The engagement of the spindles 41 with the notches 43 under the tension of the springs 45 serves to hold the impression device in this position while the paper sheet 33 is entered over the chute 32 between the separated rolls 34 and 40 and into engagement with the gage-bar 52, all as clearly shown in Fig. 2. The operator then grasps the handle 31 and, while holding the frame engaged with the fulcrum pins 49, tilts the frame down to the position indicated by dotted lines in Fig. 5. As soon as the spindles 41 of the gripping roll have passed out of the notches 43 and onto the cam surfaces 42 the continued downward swing of the forward portion of the carriage frame carries the gripping roll toward the platen roll and pinches the paper sheet between them under the action of both the springs 44 and 45. As shown in Figs. 4 and 5 the slot bearing of the spindle of the gripping roll is made of sufficient length to insure the action of the springs 44 to press the two rolls into rolling contact with each other or with the paper sheet interposed between them. The paper is thus gripped between the two rolls before the platen roll has been lowered into contact with the bed, and the final lowering of the forward end of the platen carriage carries the forward end of the sheet down onto the bed while securely held against angular displacement both by the rolls and the gage-bar. During this final movement the platen roll 34 is prevented from rotating backwardly on its axis and thus drawing the forward edge of the sheet away from the gage-bar by a brake-disk 54 (Fig. 6) carried by a spring arm 55 that is attached to one of the end bars 30 of the platen frame. This feature, however, forms a part of the invention disclosed in my former application, hereinabove identified, and is not claimed herein. As soon as the platen roll has pressed the end of the paper sheet onto the printing surface the handle 31 is raised sufficiently to clear the notches 50 from the fulcrum pins 49, whereupon the entire impression device, freed from its positioning and roll-controlling devices at the head end of the machine, may be pushed forward, as indicated in Fig. 5, thus impressing the entire sheet on the printing surface.

It is believed that the foregoing description will make clear to those skilled in the art the novel structural features of, and the improvements and advantages secured by, the invention without necessitating further detailed description. Manifestly, the details of structure and arrangement may be more or less varied without involving any departure from the principle of the invention, and hence I reserve all such detail changes and modifications as may fairly fall within the spirit and purview of the appended claims.

I claim:

1. In a multiple copying machine, the combination with a printing surface and a support therefor, of an impression device movable over said printing surface and comprising a tiltable frame, a pair of rolls carried thereby, and spring means normally urging said rolls toward each other, and co-operating devices on said support and one of said rolls, respectively, serving to separate said rolls under a tilting movement of said frame.

2. In a multiple copying machine, the combination with a printing surface and a support therefor, of an impression device movable over said printing surface and comprising a tiltable frame, a pair of rolls carried thereby, and spring means normally urging said rolls toward each other, and co-operating devices on said support and one of said rolls, respectively, serving to separate said rolls under a tilting movement of said frame and hold the latter in tilted position for the introduction of a paper sheet between said separated rolls.

3. In a multiple copying machine, the combination with a printing surface and a support therefor, of an impression device movable over said printing surface and comprising a tiltable platen frame, a platen roll journaled in said frame, a gripping roll mounted for lateral movement in said frame, and spring means normally urging said gripping roll into contact with said platen roll, and co-operating devices on said sup-

95

100

105

120

125

- port and said gripping roll, respectively, serving to separate said rolls under a tilting movement of said frame.
4. In a multiple copying machine, the combination with a printing surface and a support therefor, of an impression device movable over said printing surface and comprising a tiltable platen frame, a platen roll journaled in said frame, a gripping roll mounted for lateral movement in said frame and having spindle extensions beyond the ends of said frame, spring means normally urging said gripping roll into contact with said platen roll, and stationary members located at the opposite sides of the head end of said printing surface and formed with cam surfaces engaging the spindle extensions of said gripping roll to separate said rolls under a tilting movement of said frame.
5. In a multiple copying machine, the combination with a printing surface and a support therefor, of an impression device movable over said printing surface and comprising a tiltable platen frame, a platen roll journaled in said frame, a gripping roll mounted for lateral movement in said frame and having spindle extensions beyond the ends of said frame, spring means normally urging said gripping roll into contact with said platen roll, and stationary members located at the opposite sides of the head end of said printing surface and formed with cam surfaces engaging the spindle extensions of said gripping roll to separate said rolls under a tilting movement of said frame.
6. In a multiple copying machine, the combination with a printing surface and a support therefor, of an impression device movable over said printing surface and comprising a tiltable platen frame, a platen roll journaled in said frame, a gripping roll mounted for lateral movement in said frame and having spindle extensions beyond the ends of said frame, spring means normally urging said gripping roll into contact with said platen roll, and stationary members located at the opposite sides of the head end of said printing surface and formed with cam surfaces engaging the spindle extensions of said gripping roll to separate said rolls under a tilting movement of said frame, and also formed with notches beyond said cam surfaces to seat said spindle extensions and hold said frame in tilted position with the rolls separated for the reception of a paper sheet between them.
7. In a multiple copying machine, the combination with a printing surface and a support therefor, of an impression device movable over said printing surface and comprising a substantially rectangular tiltable frame, a pair of rolls carried thereby, and spring means normally urging said rolls toward each other, stationary members located at the opposite sides of the head end of said printing surface and provided with fulcrum bearings adapted to engage the end members of said frame, a handle on said frame, and co-operating means on said stationary members and one of said rolls, respectively, serving, when said frame is tilted on said fulcrum bearings, to effect a separation of said rolls.
8. In a multiple copying machine, the combination with a printing surface and a support therefor, of an impression device movable over said printing surface and comprising a substantially rectangular tiltable platen frame movable over said printing surface, a platen roll journaled in and between the end members of said frame and formed with spindle extensions beyond said end members, a gripping roll mounted for lateral movement in said frame and also formed with spindle extensions beyond said end members of the frame, spring means normally urging said gripping roll into contact with said platen roll, a pair of upstanding bracket plates located at the opposite sides, respectively, of the head end of said printing surface and provided with slots to engage the spindle extensions of the platen roll, cam surfaces to engage the spindle extensions of the gripping roll, and notches beyond said cam surfaces to seat said gripping roll spindle extensions, an operating handle on said platen frame, and fulcrum bearings on said bracket plates adapted to co-operate with the end members of said platen frame to effect tilting of the latter and the separation of said rolls.
9. In a multiple copying machine, the combination with a printing surface and a support therefor, of an impression device movable over said printing surface and comprising a tiltable frame, a pair of rolls carried thereby, and spring means normally urging said rolls toward each other, co-operating devices on said support and one of said rolls, respectively, serving to separate said rolls under a tilting movement of said frame, and a gage-bar located opposite the head end of said printing surface.
10. In a multiple copying machine, the combination with a printing surface and a support therefor, of a tiltable platen frame movable over said printing surface, a pair of rolls carried by said platen frame mounted with capacity for lateral movement relatively to each other and formed with spindle extensions, spring means normally urging said rolls toward each other, a pair of upstanding bracket plates located at the opposite sides, respectively, of the head end of said printing surface and provided with fulcrum bearings for tilting said frame and with means co-operating with said spindle extensions to separate said rolls and lock said platen frame against bodily movement when tilted to a position to receive a paper sheet, and a gage-bar pivotally mounted on and between said bracket plates opposite the head end of said printing surface.
11. In an impression device for multiple copying machines, the combination of a manually operated tiltable platen frame, an operating handle rigidly connected to said frame, a platen roll mounted directly and rigidly in opposite members of said frame, a paper gripping roll carried by said frame and mounted with capacity for lateral movement toward and from said platen roll, and spring means normally urging said gripping roll toward said platen roll.
12. In an impression device for multiple copying machines, the combination of a manually operated tiltable substantially rectangular platen frame, an operating

- handle mounted on one of the side bars of said frame, a platen roll mounted directly and rigidly in the end bars of said frame, a pair of arms pivoted to the end bars of said frame, a gripping roll journaled in and between said arms, and spring means acting on said arms to normally urge said gripping roll toward said platen roll.
12. In an impression device for multiple copying machines, the combination of a substantially rectangular platen frame, an operating handle mounted on one of the side bars of said frame, a platen roll journaled in and between the end bars of said frame, a pair of arms pivoted to the end bars of said frame and formed with elongated bearings, a gripping roll journaled in and between said elongated bearings, springs normally urging the bearing portions of said gripping roll toward one end of said elongated bearings, other springs acting on said arms to normally urge said gripping roll toward said platen roll, and stop devices limiting the swing of said arms in both directions.
13. In an impression device for multiple copying machines, the combination of a substantially rectangular platen frame, an operating handle mounted on one of the side bars of said frame, a platen roll journaled in and between the end bars of said frame, a pair of arms pivoted to the end bars of said frame and formed with elongated bearings, a gripping roll journaled in and between said elongated bearings, springs normally urging the bearing portions of said gripping roll toward one end of said elongated bearings, and other springs acting on said arms to normally urge said gripping roll toward said platen roll.
14. In an impression device for multiple copying machines, the combination of a substantially rectangular platen frame, an operating handle rigidly mounted on one of the side bars of said frame, a platen roll mounted directly and rigidly in the end bars of said frame, a paper gripping roll carried by said frame parallel with said platen roll and mounted with capacity for lateral movement toward and from the latter, spring means normally urging said gripping roll toward said platen roll, and a paper guide mounted on the other side bar of said frame.

JOHN J. FLANIGAN.
